(57) **CLAIM**

The ornamental design for a garment with pocket, as shown and described.

DESCRIPTION

FIG. 1 is a perspective front view of a garment with pockets in environmental conditions showing my new design;

FIG. 2 is a right side view thereof;

FIG. 3 is a left side view thereof;

FIG. 4 is a top plan view thereof;

FIG. 5 is a bottom plan view thereof;

FIG. 6 is a cross-sectional view thereof, taken along line 6-6 in FIG. 4; and,

FIG. 7 is an enlarged view thereof, taken from FIG. 6. The broken lines of the figures showing additional portions of the garment are included for the purpose of illustrating environmental structure and form no part of the claimed design.
